UNITED STATES PATENT OFFICE.

JACOB SILVERBERG, OF PITTSBURG, PENNSYLVANIA.

HEATER.

SPECIFICATION forming part of Letters Patent No. 756,721, dated April 5, 1904.

Application filed November 20, 1903. Serial No. 181,949. (No model.)

To all whom it may concern:

Be it known that I, JACOB SILVERBERG, a citizen of the United States of America, residing at Pittsburg, in the county of Allegheny and State of Pennsylvania, have invented certain new and useful Improvements in Heaters, of which the following is a specification, reference being had therein to the accompanying drawings.

10 This invention relates to certain new and useful improvements in heaters, and it relates more particularly to that type of heaters employing gas as a fuel; and the primary object of the invention is to provide a gas-heating 15 stove of novel, simple, and effective construction and comparatively inexpensive to manufacture.

A further object of the present invention is to provide means for increasing the amount of 20 heat derived from a stove of given dimensions, accomplished by increasing the burner capacity of the stove without increasing the other dimensions.

A still further object of the present invention is to provide a stove adapted for use in the same manner as an ordinary heating-stove, but which in its principle is also adapted for use for mounting on a gas-jet, if so desired.

Briefly described, the invention comprises 30 a shell or casing and a supporting-base therefor, and within the shell or casing is arranged a circular or cylindrical receptacle into which the gas is fed from a source of supply and which receptacle is perforated to permit the 35 gas to escape to the point of ignition. On the exterior surface of this receptacle is secured a covering of asbestos to throw off the heat of the burning fuel in a manner well known. A cluster of the receptacles may be arranged 40 within the shell or casing, if so desired, all fed from a common source of supply.

The construction in detail will be hereinafter more specifically described and then particularly claimed, and in describing the invention in detail reference will be had to the accompanying drawings, forming a part of this application, and wherein like numerals of reference will be employed to designate like parts throughout the different views of the drawings, in which—

Figure 1 is a central vertical sectional view of a heating-stove constructed in accordance with my invention. Fig. 2 is a similar view thereof with the shell or casing removed. Fig. 3 is a top plan view with the shell or casing removed. Fig. 4 is a plan view, partly broken away and with the casing or shell removed and the central receptacle in horizontal section. Fig. 5 is a central vertical sectional view of a modified form of construction. Fig. 6 is a top 60 plan view of another modified form of construction. Fig. 7 is a central vertical sectional view of a part of the interior receptacle in modified construction.

As shown in Figs. 1 to 4 of the drawings, 65 to construct a heating-stove in accordance with my invention I provide a suitable supporting-base 1, which may or may not be provided with supporting-feet 2, as shown. On this base is suitably mounted a cylindrical receptacle which acts as the burner, and in the present construction I have shown a convenient method of fastening, which comprises a screw 3, carried by the base 1, the base 4 of the cylindrical burner 5 being provided with 70 a threaded aperture to receive the screw 3, and thus hold the burner in position. It will of course be evident that equivalent fastening means could be employed without departing from the spirit of the invention. I prefer to 75 make the cylindrical burner corrugated, as shown, the orifices 6 provided circumferentially in the burner being preferably made in the depressions of the corrugations, the exterior of the burner having a covering of non-combustible material 7, usually of asbestos. The burner may be formed with integral upright walls and bottom, with the top 8 provided with a depending annular flange 8^a, which is secured on the upper end, or both 80 top and bottom may be made separate from the cylindrical receptacle or burner and suitably secured thereto. A supply-pipe 9 is tapped into the burner near the base, being provided with any desired form of mixer 10 and cut-off cock 11. A casing or shell 12 surrounds the burner, the lower edge of said casing or shell resting upon the base and held against lateral movement thereon in any desirable manner, as by lugs 14, carried by the 85 top and bottom of the shell 12.

base, being so placed as to fit just inside the walls of the casing or shell. This casing or shell is provided with perforations 15, through which the heated air escapes and which also 5 brings the burning fuel partly into view to add to the appearance of the stove. The casing or shell may or may not be provided with the removable cap-piece 16 in its top.

In the operation of the device just described 10 the mixed air and gas is discharged into the cylindrical burner and escapes through the openings 6, where it is ignited, the flames entirely surrounding or enveloping the burner, materially increasing the burner-surface over 15 that of an ordinary burner-back. I may provide the burner 5' with a top 8', having an overhanging flange 9', forming a deflecting-hood, as seen in Fig. 7, against which the flames would strike so as to deflect the same 20 outwardly.

In Fig. 5 I show the adaptation of the same principle to a heater to be attached direct to a gas-jet leading out from the wall or other point. In this construction the base 17 has a 25 mixer 18 fitted centrally therein, which mixer receives the tip of the gas-jet 19. The mixer carries a screw or threaded stud 20, onto which the burner 21 is secured, the burner being of the same construction as shown in 30 Figs. 1 to 4. The base 17 is provided with an annular flange 22, within which the shell or casing 23 fits, the said shell or casing being provided with a suitable cover 24 and being preferably provided with perforations 25. 35 In Fig. 6 I show the adaptation of the same principle to a stove having a cluster of burners, the shell or casing 26 inclosing all the

burners 27, which are arranged in any desired form in their cluster, the supply-pipe leading, preferably, to the central burner of the cluster and branch feed-pipes 28 leading to the remaining burners of the cluster. 40

The employment of the cylindrical burner, as shown and described, provides a large amount of burner-surface within a comparatively small space, as will be readily apparent. 45

With this construction of burner it is to be observed that the gas being discharged into the circular burner and fed out therefrom all around the burner all of the gas is utilized, 50 thus materially increasing the heat thrown off by the heater.

While I have herein shown and described the invention in detail as it has been practiced by me, yet it will be evident that various 55 slight changes may be made in the details without departing from the general spirit of the invention.

Having fully described my invention, what I claim as new, and desire to secure by Letters 60 Patent, is—

In a heater of the type described, a corrugated cylindrical burner provided with perforations and having a covering of non-combustible material, an annular depending flange 65 carried by said burner at its upper end forming a deflector, and a supply-pipe communicating with the burner.

In testimony whereof I affix my signature in the presence of two witnesses.

JACOB SILVERBERG.
